Primary Examiner — Carla J Wright

(57) **CLAIM**

The ornamental design for a film applicator for mobile phone as shown and described.

DESCRIPTION

1. Film applicator for mobile phone

1.1 : Front

1.2 : Back

1.3 : Left

1.4 : Right

1.5 : Top

1.6 : Bottom

1.7 : Perspective

1.8 : Perspective

Reproduction 1.1 is a front view of a film applicator for mobile phone showing our new design; reproduction 1.2 is a back view thereof; reproduction 1.3 is a left view thereof; reproduction 1.4 is a right view thereof; reproduction 1.5 is a top view thereof; reproduction 1.6 is a bottom view thereof; reproduction 1.7 is a top, front and right side perspective view thereof; and reproduction 1.8 is a top, back and left side perspective view thereof.

1 Claim, 8 Drawing Sheets
